STAPLING MACHINE

Thomas J. Finn, West Roxbury, Mass.

Application February 12, 1952, Serial No. 271,176

7 Claims. (Cl. 1-2)

1

This invention relates to improvements in stapling machines and relates more particularly to stapling machines of the general type suitable for attaching buckles to straps or to other flexible elements or flexible sheets.

In the shoe industry, and more especially in the manufacture of women's and children's shoes, the attachment of buckles to straps, or to other portions of shoe uppers, has involved problems which the prior buckle-attaching mechanisms and procedures have not been able to solve in any satisfactory or adequate manner. Buckles are attached either by stitching or by staples, and the requirement for a stitched or stapled securing of a buckle at two locations on opposite sides of the pivoted tongue of the buckle, has made it necessary for the operator of a sewing machine, or a prior stapling machine, to manually shift the work following completion of a securing at one side of the buckle tongue, preparatory to effecting the second securing at the other side of the tongue. This not only has consumed valuable time but has required the operator to manually shift the work laterally on the supporting anvil in proper timed relation to the next descent of the sewing machine needle or the next staple-driving operation of a stapling machine. Actually, buckles frequently have become attached in a skewed relation to a strap. Also, due to the difficulties the operator encounters in properly gauging the amount of each lateral shifting of the work needed to get the second securing in proper relation to the tongue of any particular buckle, and in properly timing the shift with relation to the next descent of the needle of a sewing machine, or the next staple-driving operation of a stapling machine, sewing machine needles frequently become broken by coming in contact with buckle tongues and pivot bars, and staples frequently are destroyed or misdirected by coming in contact with those same elements when buckles are being attached by stapling machines. In either case, further time is lost to correct the difficulty and to remove any improperly introduced stitches or staples. However, even the correctly accomplished buckle securities, attained with the prior stitching and stapling machines in accordance with prior buckle-attaching procedures, have been objectionable in that the stitched securities frequently provide discomforting hard masses of thread at the inner side of the upper material which comes next to the foot of the wearer of a shoe. Also, when buckles are stitched on, the securing threads frequently break after a relatively

2

short period of use of a shoe, making it necessary to re-secure a buckle or to replace a lost buckle. When buckles have been stapled to shoe uppers, the more common procedure has been to clinch the staples at the inner surface of the upper material which comes next to the foot of the wearer of a shoe, and there is always danger that an imperfectly driven and clinched staple will have an exposed end or a burr capable of injuring a foot in the shoe or of snagging and causing a run in the wearer's stocking. Prior stapled-on buckles also have been subject to loosening and falling off.

While efforts have been made heretofore to effectively attach shoe buckles by means of staples driven through shoe upper material so that the bridges or crowns of the staples are at the inner surface of the upper material which comes next to the foot of a wearer of the shoe, no one prior to my present invention, so far as I am aware, has been able to accomplish this desirable end in any practicably acceptable manner so far as outward appearance of the attached buckles is concerned and so far as facility of effecting the stapled attachments of the buckles, on principles of mass production of shoes, is concerned.

Hence, it is among the objects of my present invention to provide a stapling machine whereby shoe buckles may be effectively stapled to shoe upper materials with utmost assurance that any particular buckle will be secured by two generally parallel successively driven staples in a predetermined precise spaced relation on opposite sides of the pivoted tongue of the buckle. In accordance with the teachings of my invention, an operator merely holds the portion of a shoe upper to which a buckle is to be attached in proper relation to a buckle on a supporting anvil while effecting two staple-driving operations of a stapling machine, and the anvil automatically shifts the work in precisely timed relation to the second staple-driving operation of the machine, thereby to precisely locate the first and second staples in predetermined spaced parallelism at opposite sides of the pivoted tongue of the buckle.

Another object of the invention is to provide a stapling machine for attaching buckles to shoe uppers, wherein an anvil is designed to directly support a buckle with a portion of its pivot bar, which is to one side of the pivoted tongue of the buckle, opposite the staple delivering nose of the stapling machine, whereby the first of two staples delivered through said nose in rapid succession is clinched around said portion of the pivot bar of

the buckle, the anvil shifting automatically following clinching of the first-delivered staple to bring a second portion of the pivot bar, which is to the opposite side of the pivoted tongue of the buckle, opposite the staple delivering nose of the machine prior to delivery of the second staple, whereby the second of the two staples is clinched around said second portion of the pivot bar of the buckle.

A further object of my invention is to provide a buckle stapling machine having an anvil for directly supporting a buckle under a staple-delivering head with space between the buckle and head for insertion of a strap or other flexible work piece upon the buckle, whereby a staple driven from said head through the strap, or other work piece, may be clinched around a part of the buckle with the bridge or crown of the staple at one side of the strap, or other work piece, and with the buckle secured to the other side by legs of the staples which are clinched in parallelism and whose pointed ends are turned into and embedded in the material of the strap, or other work piece, at that side to which the buckle is secured.

It is, moreover, my purpose and object generally to improve stapling machines and stapling procedures, and more especially such machines and procedures which are suitable for stapling buckles to strap portions of shoe uppers, and the like.

In the accompanying drawing:

Fig. 1 is a side elevation of a stapling machine embodying features of my invention, the machine being for the most part in medial vertical cross-section;

Fig. 2 is a top plan view of the anvil and the forward portion of its supporting lever, parts of the supporting lever being broken away;

Fig. 3 is a cross-sectional view on line 3—3 of Fig. 2, on a larger scale, and showing the staple-delivering nose, a buckle and strap, and a staple in clinched relation to the buckle and strap;

Fig. 4 is a cross-sectional view on line 4—4 of Fig. 3, showing two clinched staples on opposite sides of the pivoted tongue of the buckle; and

Fig. 5 is a cross-sectional view on line 5—5 of Fig. 1, on the scale of Fig. 1.

Referring to the drawing, the invention is illustrated as embodied in a buckle-stapling machine having a staple forming head 10 which is adapted to deliver formed staples in succession through the nose 12 of the head, as more particularly described in my Patent No. 2,417,817, dated March 25, 1947, to which reference is made for a description of the staple forming and staple driving mechanism within the head 10, and of suitable means (not herein shown) for advancing a strand of wire intermittently into the head from a supply reel. It should be understood, however, that the illustrated head 10 is representative of stapling machine heads in general which are adapted to drive staples in succession, in conjunction with a work-supporting and staple-clinching anvil.

Head 10 is mounted on an upper forwardly-projecting hollow part 14 of a hollow base standard 16 which may rest on a bench 18, or other suitable support. A generally horizontally disposed power shaft 20 is rotatable within the forwardly projecting hollow part 14 of the base standard, and has a cam 22 fixed on its forward end, within the head 10, for actuating the staple forming, staple driving and wire feeding means as disclosed in my said patent.

The rear end portion of power shaft 20 extends out of hollow part 14 and is equipped with a

clutch mechanism 24 by means of which the power shaft may be operatively connected at will for rotation with a pulley 26 which may be belt-driven from any suitable source of power. The clutch mechanism 24 may be controlled by an actuating member 28 whose lower end may be operatively connected for pedal actuation by the operator of the machine.

According to the invention, a clinching anvil, indicated generally at 30, is mounted for reciprocation at the forward portion of arm 32a of a bell-crank lever 32. The bell-crank lever is pivotally mounted at 34 within the base standard 16, and the arm 32a of the bell-crank extends forwardly through an opening 36 in the forward wall of the base standard 16 to a location below the delivery nose 12 of head 10. The other and shorter arm 32b of the bell-crank extends upwardly within the base standard and preferably is equipped at its upper end with a roller 33 which is in coating relation with a cam 38 fixed on the power shaft 20.

Bell-crank lever 32 is of rugged construction for withstanding the substantial stresses imposed upon it. As best seen in Fig. 2, its arm 32a has considerable width, and its forward end portion is grooved longitudinally at its upper side, as at 40, and an anvil carrying member 42 is slidably mounted in the groove 40 and is retained therein by a bolt 44 which extends through the rear end portion of member 42, through a slot 46 in the bottom wall of groove 40, and through the forward end of a second slidably mounted member 48 to which it is secured by nut 45 on the end of bolt 44. Member 48 is mounted in a relatively shallow longitudinal groove 50 in the under side of arm 32a of bell-crank lever 32 at the rearward portion of its extent and is further retained, slidably, in groove 50, by a screw 52 which passes loosely through a slot 54 in member 48 and is screwed into the arm 32a, with a washer 56 preferably intervening between the head of screw 52 and the adjacent surface of member 48. The two slidably mounted members 42 and 48 thus are mounted in connected relation on arm 32a for sliding movements as a unit relative to arm 32a of the bell-crank.

The anvil-carrying slidable member 42 constantly is biased toward the limit of its forward movement in groove 40 by a coil spring 58 which is under compression between the rear end of slidable member 42 and an upstanding part 32' on lever arm 32a. Preferably, this forward limit of movement of member 42 is made adjustable by means of a relatively long threaded rod or pin 60 about which spring 58 is coiled, one end of the rod or pin 60 being fixed at 62 to the rear end of slidable member 42. The rod or pin extends from its securing at 62 through spring 58 and loosely through a hole 64 in the upstanding part 32' of lever arm 32a, with a finger nut 66 screwed on the projecting threaded end portion of rod or pin 60 and engaging the part 32' of lever arm 32a. Preferably, a second finger nut 68 on the rod or pin 60 serves as a lock nut.

The clinching anvil 30 is shown removably secured to the forward end of slidable member 42 by the two screws 70 and is steadied on slidable member 42, in the illustrated embodiment, by being seated in a groove 72 in the upper side of member 42. Actually, the illustrated clinching anvil 30 is especially designed for directly supporting buckles in the process of stapling the buckles to flexible elements, such as to straps or other portions of shoe uppers, for example. The

anvil has two similar staple-clinching portions 30a, 30b spaced apart in the direction of extent of the anvil on the slideable member 42 to provide a groove 30' between them for accommodating the tongue of a buckle placed on the anvil. In Fig. 2, a buckle B is shown mounted on anvil 30 with its tongue T extending at the under side of the buckle and positioned within the anvil groove 30'. A strap portion of a shoe upper is represented by dotted outline at S in Fig. 2 and is shown by full lines, on a larger scale, in Figs. 3 and 4. In the process of stapling the buckle to such a strap portion, the operator places the strap portion S on the buckle B between the supported buckle and the nose 12 of the staple-delivering head 10 so that the bridge of each driven staple is at the upper side of the strap portion and the buckle is secured to the under side of the strap portion.

The tongue T of buckle B is pivotally mounted in a customary manner on the usual centrally disposed pivot bar B' of the buckle and this pivot bar B', when the buckle is placed on anvil 30, is disposed transversely of anvil groove 30' with the buckle tongue T in groove 30' and with portions of the pivot bar B', on opposite sides of tongue T, resting respectively across the clinching portions 30a and 30b of the anvil. Preferably, the clinching portions 30a, 30b, are provided with the shallow transverse notches 30c in which the pivot bar B' seats to facilitate proper centering of the buckle relative to the clinching portions of the anvil.

Each clinching portion 30a, 30b of the anvil has a groove 30d in its upper face with walls for engaging and clinching the legs of driven staples and, according to the invention, after a buckle B has been arranged on the anvil 30, as in Fig. 2, and while a strip portion S is held by the operator on and in proper relation to the buckle, the staple-clinching portion 30a will be under the nose 12 of head 10, in position for a first-delivered staple to be driven through strip portion S and to be clinched, by clinching portion 30a, around the pivot bar 30' of the buckle to the left of buckle tongue T, as viewed in Fig. 2. However, before said first staple can be driven, bell-crank lever 32 is rocked slightly by cam 38 counter-clockwise in Fig. 1, to bring anvil 30, and the work thereon, into coaxing relation to nose 12.

As soon as said first staple is driven and clinched, the anvil and work drop a little away from nose 12 as the bell-crank roller 33 rides from the high side of cam 38 into engagement with an adjustable stop 74 which limits the amount that the anvil 30 can move in direction away from nose 12. The bell-crank is gravity-actuated clockwise, in Fig. 1, to bring the arm 32b into engagement with stop 74. Following this dropping away of anvil 30 and the supported work, and before cam 38 again rocks the bell-crank to move the anvil a second time toward nose 12, the anvil is actuated to the left in Fig. 1 to bring clinching portion 30b under the nose 12. The work on the anvil moves with the anvil to bring that portion of pivot bar 30' of the buckle which is to the right of tongue T, as viewed in Fig. 2, under nose 12. Hence, as anvil 30 moves upward a second time toward nose 12, the second staple is driven through strip portion S and is clinched by clinching portion 30b around the pivot bar 30' of the buckle to the right of tongue T.

The mentioned actuation of anvil 30 to the left in Fig. 1 is accomplished by a cam 76, or

the like, which is fixed on a shaft 78 mounted low down within the base standard 16. Shaft 78 is driven from power shaft 20 by any suitable drive means such as the illustrated chain 80 engaging around a sprocket 82 fixed on power shaft 20 and a sprocket 84 fixed on shaft 78. The sprocket 82 has one-half the diameter of sprocket 84, and cam 38 on power shaft 20 similarly has one-half the diameter of cam 76 on shaft 78. Hence, cam 38 makes two complete rotations, and effects two movements of anvil 30 toward nose 12, while cam 76 on shaft 78 is making one complete rotation.

Slide member 48 at the under side of lever arm 32a has a rigid depending portion 48a whose lower end preferably is equipped with a roller 48b in coaxing relation to cam 76, and the high part of the cam 76 is designed to force roller 48b to the left in Fig. 1 during alternate movements of anvil 30 toward nose 12. Inasmuch as depending portion 48a is rigid on slide member 48, and slide member 48 is connected by bolt 44 to anvil-carrying slide member 42, the anvil 30 is moved to the left in Fig. 1, with compression of spring 58, each time that roller 48b is forced to the left by cam 76, and spring 58 restores anvil 30 to its original position as soon as roller 48b leaves the high part of cam 76.

It is a feature of the invention that each of two staples driven in relatively rapid succession become accurately positioned automatically on opposite sides of the buckle tongue and become clinched around the pivot bar of the buckle in a superior manner. Referring more particularly to Fig. 3, wherein the first of two buckle-securing staples is shown clinched around the pivot bar B' of buckle B, it will be seen that the staple driver 13 indents the bridge or crown of the staple into the strap member S at that side of strap member S which is opposite the side to which buckle B is secured, and that each leg of the staple is clinched around pivot bar B' to an extent whereby the pointed end of each leg is driven into and embedded in the material of strap member S, with the clinched legs in side-by-side relation in groove 30d of clinching portion 30a of anvil 30. An extremely strong stapled securing of buckle B is thus attained with a relatively smooth upper surface of strap portion S, in Fig. 3, which is the inner surface of the strap member when in use in a shoe, for example. The pointed ends of the staple legs are embedded in the strap portion S at its under and outer side whereby they cannot harm a foot or snag hosiery, or otherwise cause discomfort or damage to whatever may be in contact with the side of strap portion S which is the inner side in service.

Fig. 4 is a cross-sectional view on line 4-4 of Fig. 3 showing the anvil 30 moved to the left from its dotted line position, following driving and clinching of the first staple, which is shown clinched in groove 30d of clinching portion 30a of the anvil, and showing the second staple driven and clinched in groove 30d of clinching portion 30b of the anvil. As soon as the anvil and work, as represented in Fig. 4, drops away from nose 12, spring 58 returns anvil 30 to the right to again position clinching portion 30a under nose 12, as represented in Fig. 1, after which the completed work is removed and another buckle B and strap portion S may be arranged on the anvil and the disclosed double stapling procedure repeated.

It is intended that the patent shall cover, by suitable expression in the appended claims, whatever features of patentable novelty exist in the invention disclosed.

I claim as my invention:

1. A stapling machine having, in combination, a fixed staple-delivering head, means operative within said head for driving staples in rapid succession from the head, a support mounted for movement in directions toward and from the staple-delivering portion of said head, a work-supporting clinching anvil movably mounted on said support and having two spaced staple-clinching portions thereon, mechanism for moving said support and the anvil toward and from said head a plurality of times in rapid succession and in timed relation to the delivery of successive staples from the head, and means for rapidly reciprocating said anvil and the work thereon between two positions on said support to bring said two clinching portions of the anvil alternately into clinching relation to successively delivered staples.

2. A stapling machine having, in combination, a fixed staple-delivering head, means operative within said head for driving staples in rapid succession from the head, a support mounted for movement in directions toward and from the staple-delivering portion of said head, a work-supporting clinching anvil slidable on said support and having two spaced staple-clinching portions thereon, mechanism for moving said support toward and from said head a plurality of times in rapid succession thereby to move the anvil intermittently into clinching relation to successively delivered staples, and means operative to rapidly reciprocate the slidably mounted anvil on said support to bring said two staple-clinching portions of the anvil alternately into clinching relation to successively delivered staples.

3. A stapling machine comprising, in combination, a fixed staple-delivering head, means operative within said head for driving staples in rapid succession from the head, a staple clinching anvil in coacting relation to the delivery portion of said head and having two spaced relatively fixed clinching portions thereon, a support for said anvil movable toward and from said delivery portion of the head, means for moving said support toward said head each time that a staple is to be driven from said head thereby to move the anvil into clinching relation to each delivered staple, and means operative to rapidly reciprocate said anvil on its said support in directions to bring said staple-clinching portions of the anvil alternately into said clinching relation to successively delivered staples.

4. A stapling machine comprising, in combination, a head with a fixed staple-delivering nose, means operative to drive staples in rapid succession through said nose, a staple-clinching anvil disposed opposite said nose, a pivotally mounted support for said anvil, means for rocking said support in direction to move said anvil toward said nose each time that a staple is to be driven through said nose whereby the anvil clinches each driven staple, said anvil having a plurality of spaced staple-clinching portions thereon and being slidably retained on its said pivotally mounted support, and means for rapidly reciprocating the anvil on its said support thereby to clinch successively driven staples by

different ones of said plurality of staple-clinching portions of the anvil.

5. A stapling machine comprising, in combination, a fixed staple-delivering head with means for driving formed staples in rapid succession through the delivery portion of said head, a combined work support and clinching anvil disposed opposite said delivery portion of said head, a pivoted support for said anvil, means for rocking said support to move the anvil and work thereon toward said head each time that a staple is to be driven thereby to bring said anvil into clinching relation to each driven staple, said anvil having two separated staple-clinching portions thereon and being movable between two predetermined positions on its said support, and means for rapidly shifting said anvil on its support from one to the other of said positions following clinching of each driven staple whereby each of said staple-clinching portions of the anvil clinches alternate ones of successively driven staples.

6. A buckle-stapling machine comprising, in combination, a fixed staple-delivering head with means for driving formed staples in rapid succession through the delivery portion of said head, a clinching anvil disposed opposite said delivery portion of said head and having a pair of staple-clinching portions with a groove between them, said anvil being adapted to directly support a buckle with the pivoted tongue of the buckle accommodated in said groove and with the pivot bar of the buckle disposed transversely across the groove with a portion crossing each of said staple-clinching portions of the anvil, a pivoted support for said anvil on which said anvil is movable between two positions, means for rocking said support toward said head each time that a staple is to be driven thereby to move said anvil to staple-clinching position, and means for moving said anvil on its said support rapidly from one to the other of its two said positions following each clinching of a driven staple whereby a first driven staple becomes clinched around a portion of said pivot bar of the buckle to one side of the buckle tongue by one of said staple-clinching portions of the anvil, and a second driven staple becomes clinched around a portion of said pivot bar to the other side of said tongue by the other of said staple-clinching portions of the anvil.

7. A power driven stapling machine comprising, in combination, a fixed staple-delivering nose with means for driving formed staples in rapid succession through said nose, means for directly supporting a buckle opposite said nose with the pivot bar for the tongue of the buckle disposed transversely of the direction of extent of the bridge part of each driven staple, said buckle-supporting means having two spaced staple-clinching portions thereon with a groove between them, and the tongue of a said buckle being accommodated by said groove when the buckle is supported with the tongue at the under side thereof, a pivoted lever having an arm on which said buckle-supporting means is movable, in the directions of extent of said pivot bar of the supported buckle, between two predetermined positions, means for rocking said lever to move the supported buckle toward said nose each time that a staple is to be driven, and means for moving said buckle supporting means on its said lever arm from one to the other of its said two positions following each said movement of a supported buckle toward said nose, whereby first and second driven staples become clinched around

said pivot bar of the buckle at opposite sides of the buckle tongue by different ones of said staple-clinching portions of the buckle supporting means.
